Primary Examiner — Patricia Palasik

(57) **CLAIM**

The ornamental design for a linear guideway, as shown and described.

DESCRIPTION

FIG. 1 is a front elevational view of a linear guideway showing my new design;

FIG. 2 is a top plan view thereof;

FIG. 3 is a bottom plan view thereof;

FIG. 4 is a left side elevational view thereof; a right side elevational view is a mirror image of the left side elevational view;

FIG. 5 is a front, right perspective view thereof;

FIG. 6 is a rear, right perspective view thereof;

FIG. 7 is a top, right perspective view thereof; and,

FIG. 8 is a bottom, right perspective view thereof.

1 Claim, 2 Drawing Sheets(56)
